UNITED STATES PATENT OFFICE.

FREDERICK W. DAVIS, OF DAYTON, OHIO.

WATER-STATION.

1,345,482.

Specification of Letters Patent. Patented July 6, 1920.

Application filed June 26, 1919. Serial No. 306,884.

To all whom it may concern:

Be it known that I, FREDERICK W. DAVIS, citizen of the United States, residing at Dayton in the county of Montgomery and State 5 of Ohio, have invented certain new and useful Improvements in Water-Stations, of which the following is a specification.

This invention relates to an improved water station particularly designed for use 10 by automobilists for filling or replenishing automobile radiators with water.

The invention has as one of its principal objects to provide a device whereby an automobile radiator may be easily and quickly 15 filled without spilling the water while likelihood of running the radiator over will be reduced to a minimum.

The invention has as a further object to provide a device which will be readily accessible and of such nature that an automobile 20 radiator may be filled without soiling or wetting the hands.

And a still further object of the invention is to provide a device wherein the discharge 25 pipe employed will be extensible so that the discharge faucet of the device may be readily positioned over the filler tube of a vehicle radiator and wherein, upon the release of the discharge pipe it will be returned to 30 and normally held in a position lying beneath the canopy of the casing of the device.

Other and incidental objects will appear hereinafter. In the drawings:

Figure 1 is a perspective view of my improved water station,

Fig. 2 is a vertical sectional view on an enlarged scale, this view more particularly showing the structural details of the device,

Fig. 3 is a transverse sectional view taken 40 on the line 3—3 of Fig. 2 and looking in the direction of the arrows, and

Fig. 4 is a transverse sectional view showing the manner in which the discharge pipe of the device may be extended.

Referring more particularly to the drawings, I employ a preferably elliptical casing 10 which may be constructed of sheet metal or other approved material. At its upper end, the casing is provided with an overlying canopy or hood 11. This canopy is open at its sides and may be formed integral with the casing or otherwise secured thereto. The casing is designed to be set into the ground or otherwise mounted at some convenient location. For instance, the device 55 may be arranged adjacent a street curbing

or may be located as suggested in Fig. 1, a driveway being provided around the device so that vehicles may be driven up at either side of the device. Upstanding within the 60 casing is a water supply pipe 12 in communication with a suitable source of water supply and swiveled upon the upper end of this pipe in a plane above the upper edge of the casing is the inner section 13 of a discharge pipe, the outer section 14 of which is, in turn, swiveled to the inner section. Connected to the outer section 14 of the discharge pipe is a flexible armored hose 15, the armor around said hose being sufficiently 65 rigid to normally maintain the hose in alignment with said pipe section, and connected with the hose at its outer end is a discharge faucet or nozzle 16. This faucet may be of any approved character but is preferably of 70 the type having a spring pressed valve operated by a lever 17 which must be manually held depressed in order to permit a flow of water through the faucet. A faucet of this type will prevent wasting of the water. 80

Extending across the casing 10 adjacent the upper end thereof are spaced bars 18 and mounted between these bars medially of the casing are confronting pulleys 19. Trained between said pulleys is a cable or other approved flexible element 20 connected at its upper end to the inner end portion of the section 13 of the discharge pipe. A spring 21 is secured to the lower end of said cable and engaged with the spring is a weight 22. 90 Connected at one end to the outer end portion of the section 13 of the discharge pipe is a spring 23, the opposite end of which is connected to the inner end portion of the section 14 of said pipe. 95

As will now be clear in view of the preceding description, the spring 23 will normally hold the section 14 of the discharge pipe in a position overlying the section 13 of said pipe while the weight 22 will act upon the latter section for normally holding both of the sections in inactive position lying beneath the canopy 11. However, when it is desired to fill an automobile radiator, the section 14 of the discharge pipe may be 100 grasped when, as suggested in Fig. 4, said pipe section together with the section 13 of the discharge pipe, may be swung outwardly or extended from beneath the canopy until the faucet 16 is brought to a position over 110 the radiator filler tube. Since the radiators of different vehicles will vary in height, the

hose 15 is provided. As will be seen, this hose may be flexed so that the faucet may be inserted into the radiator filler tube when, by manually depressing the lever 17, the radiator may be filled with water. Since this lever provides a means whereby complete manual control may be had over the flow of water through the faucet 16, spilling of the water will be prevented while likelihood of 5 running the radiator over will be reduced to a minimum. Upon the filling of the radiator, the section 14 of the discharge pipe may simply be released when the weight 22 and spring 23 will serve to return the sections of 10 the pipe to their normal position beneath the canopy 11. To avoid bursting of the pipe in cold weather, a combined shut-off valve and drain cock 24 is interposed in the supply pipe 12 and formed through the casing 10 opposite the hand wheel of this valve is an 15 opening 25 through which the valve may be operated.

Having thus described the invention, what is claimed as new is:

25 1. A device of the character described including a casing provided with a canopy having its intermediate portion spaced upwardly from the adjacent portion of the casing thereby forming openings on opposite 20 sides of the casing, a water supply pipe, a discharge pipe in communication with said water supply pipe, means for controlling the flow of water through the discharge pipe, and means for normally holding the 25 discharge pipe beneath said canopy.

2. A device of the character described including a casing provided with a canopy having its intermediate portion spaced from the adjacent portion of the casing thereby 40 forming openings on opposite sides of the casing, a water supply pipe disposed within the casing, a discharge pipe in communication with said water supply pipe and movable through said openings, a discharge nozzle, a flexible connection between the nozzle and said discharge pipe, and yieldable means for normally retaining said discharge pipe beneath said canopy.

3. A device of the character described including a casing provided with a canopy having its major portion spaced from the casing thereby forming an opening, a water supply pipe upstanding within the casing, a rigid discharge pipe swiveled to the 50 upstanding pipe and extending angularly from the same, the discharge pipe being exten-

sible to project beyond the canopy, means for normally holding the discharge pipe beneath the canopy, and a valve for controlling flow through the discharge pipe. 60

4. A water supply station for motor vehicles including a casing, a water supply pipe extending vertically within the casing, a horizontal pipe section swiveled to the upper end of the supply pipe and movable 65 about a vertical axis, a second pipe section swivelly connected to one end portion of said first named pipe section and movable about a vertical axis, a flexible hose section secured to one end of said second named 70 pipe section, a faucet connected to the forward end of said flexible hose, spring means to normally retain said second named pipe section above said first named pipe section, and means connected to said first named pipe 75 section for normally retaining the same within said casing.

5. A water supply station including a casing having its sides open, a horizontally arranged pipe section disposed within said casing and having one end portion movable about a vertical pivot, a flexible element connected to said pipe section and having its lower end provided with a weight adapted for normally retaining said pipe 85 section within the casing, said means carried by said housing for said flexible element, a second pipe section arranged above said first named pipe section and swivelly connected to one end of the same, a coil 90 spring connected to the adjacent end portions of said first and second named pipe sections for normally retaining said second named pipe section directly above said first named pipe section, and a faucet arranged 95 at the outer end of said second named pipe section.

6. The combination with a casing having a canopy, of a water supply member arranged within the casing, a pipe section 100 operatively connected to said water supply member, a second pipe section operatively connected to the first named pipe section and movable outwardly of said canopy, a flexible element connected to said first named pipe 105 section and having means for returning the pipe section to beneath said canopy upon being released at a point spaced from the casing, and guiding means for said flexible element.

In testimony whereof I affix my signature.
FREDERICK W. DAVIS. [1. s.]
